FIG. 1

FIG. 2

To all whom it may concern:

Be it known that we, George H. Kress and Carl W. Sundberg, citizens of the United States of America, residing, respectively, at Endwell, county of Broome, State of New York, and Birmingham, county of Oakland, State of Michigan, have invented a new, original, and ornamental Design for a Magnetic Tape Unit, of which the following is a specification, reference being had to the accompanying drawings, forming part thereof.

Fig. 1 is a perspective view of a magnetic tape unit, embodying our design.

Fig. 2 is a rear perspective view of the same.

The dominant features of our design reside in those portions shown in full lines.

We claim:

The ornamental design for a magnetic tape unit, as shown and described.
